EYE FOR FISHING LURES

Theodore Kandz, 2240 Curtis Drive N.,
Clearwater, Fla. 33516

Filed Apr. 21, 1967, Ser. No. 6,782

Term of patent 14 years

(Cl. D22—27)

FIG. 1

FIG. 2

FIG. 3

FIG. 4

FIG. 5

FIG. 1 is a front elevation of an eye for fishing lures showing my new design.

FIG. 2 is an enlarged front elevation thereof;

FIG. 3 is an enlarged rear elevation thereof;

FIG. 4 is an enlarged side and plan view thereof; and

FIG. 5 is an enlarged cross sectional view taken through section line 5—5 of FIG. 1.

The dotted lines shown are for illustrative purposes only.

I claim:

The ornamental design for an eye for fishing lures, as shown and described.
